(57) CLAIM

The ornamental design for a correction tape dispenser, as shown and described.

DESCRIPTION

FIG. 1 is a top perspective view showing our new design for a correction tape dispenser;

FIG. 2 is a right side view of the correction tape dispenser of FIG. 1;

FIG. 3 is a left side view of the correction tape dispenser of FIG. 1;

FIG. 4 is a front view of the correction tape dispenser of FIG. 1;

FIG. 5 is a rear view of the correction tape dispenser of FIG. 1;

FIG. 6 is a top plan view of the correction tape dispenser of FIG. 1; and,

FIG. 7 is bottom plan view of the correction tape dispenser of FIG. 1.

The broken lines shown in the drawings represent portions of the correction tape dispenser that form no part of the claimed design.

1 Claim, 3 Drawing Sheets
